(57) **CLAIM**

The design for an over machine garment rack, as shown and described.

DESCRIPTION

FIG. 1 is a front perspective view of the design of the over machine garment rack of the present invention;

FIG. 2 is a front elevation view of the over machine garment rack embodiment shown in FIG. 1;

FIG. 3 is a rear elevation view of the over machine garment rack embodiment shown in FIG. 1;

FIG. 4 is a side elevation view of the over machine garment rack embodiment shown in FIG. 1;

FIG. 5 is a bottom plan view of the over machine garment rack embodiment shown in FIG. 1;

FIG. 6 is a top plan view of the over machine garment rack embodiment shown in FIG. 1;

FIG. 7 is a perspective view of the over machine garment rack embodiment shown in FIG. 1 in environment with an appliance (not claimed);

FIG. 8 is a front perspective view of a design of the over machine garment rack of the present invention;

FIG. 9 is a front elevation view of the over machine garment rack embodiment shown in FIG. 8;

FIG. 10 is a rear elevation view of the over machine garment rack embodiment shown in FIG. 8;

FIG. 11 is a side elevation view of the over machine garment rack embodiment shown in FIG. 8;

FIG. 12 is a bottom plan view of the over machine garment rack embodiment shown in FIG. 8; and,

FIG. 13 is a top plan view of the over machine garment rack embodiment shown in FIG. 8.

The broken lines depict environmental subject matter only and form no part of the claimed design.

The break lines shown in FIGS. 8 through 13 are not part of the claimed design and represent that no particular length is claimed.
